FIG. 1 is a perspective view of a door handle, lock housing and plate ensemble in accordance with the preferred embodiment of my invention showing the ensemble mounted on both sides of a glass plate of the type used in glass doors;

FIG. 2 is a rear view of the embodiment shown in FIG. 1 and is a mirror image of a front view;

FIG. 3 is an enlarged elevation taken from either side since both side views are identical;

FIG. 4 is an enlarged top view of the embodiment as shown in FIG. 2;

FIG. 5 is an enlarged bottom view of the embodiment as shown in FIG. 2;

FIG. 6 is a greatly enlarged section taken as indicated by the lines and arrows 6—6 in FIG. 3;

FIG. 7 is a greatly enlarged section taken as indicated by the lines and arrows 7—7 in FIG. 3;

FIG. 8 is a perspective view of a door handle, lock housing and plate ensemble embodying my new design in an elementary form, shown mounted in its environmental condition on the flat surface of a plate shown in phantom lines;

FIG. 9 is a front elevation of the embodiment shown in FIG. 8;

FIG. 10 is an enlarged right side view of the embodiment shown in FIG. 8;

FIG. 11 is an enlarged top view of the embodiment as shown in FIG. 9;

FIG. 12 is an enlarged bottom view of the embodiment as shown in FIG. 9;

FIG. 13 is a greatly enlarged section of a portion of the ensemble taken as indicated by the lines and arrows 13—13 in FIG. 10;

FIG. 14 is a greatly enlarged section of a portion of the housing taken as indicated by the lines and arrows 14—14 in FIG. 10;

FIG. 15 is a view of a door handle, lock housing and plate ensemble in accordance with another embodiment of my invention, shown mounted in its environmental condition on the flat surface of a plate shown in phantom lines;

FIG. 16 is a front elevation of the embodiment shown in FIG. 15;

FIG. 17 is an enlarged right side view of the embodiment shown in FIG. 15; and

FIG. 18 is an enlarged top view of the embodiment as shown in FIG. 17.

Portions have been foreshortened in the drawings for convenience of illustration.

The structure shown in dotted lines forms no part of the invention but is an expedient to best illustrate environment only.

This application incorporates by reference the disclosures of my prior copending applications Ser. No. D. 21,816, filed: Mar. 9, 1970 for a "Combined Door, Push Plate, and Door Handle and Lock Housing Unit," and Ser. No. D. 23,254, filed: June 1, 1970 for a "Door," and discloses and claims, in part, the subject matter of these applications.

I claim:

The ornamental design for a door handle, lock housing and plate ensemble, as shown and described.
